H. GENGBRE HUBERT, OF NEW YORK, N. Y.

Letters Patent No. 72,201, dated December 17, 1867

IMPROVEMENT IN FURNACES FOR SMELTING PRECIOUS METALS.

The Schedule referred to in these Letters Patent and making part of the same.

Be it known that I, H. GENGBRE HUBERT, of the city, county, and State of New York, have invented certain Improvements in Furnaces for Smelting Precious Metal Ores; and I do hereby declare that the following is a full and exact description thereof, reference being had to the accompanying drawings, in which—

Figure 1 represents a sectional elevation, through $z z$, of a cupola-furnace built on my improved plan.

Figure 2 is a horizontal section, through $x x$, of the same.

Figure 3 is a sectional elevation of a reverberatory furnace; and

Figure 4 is also a sectional elevation of a reverberatory furnace, both having my improvement applied.

This invention relates to an improved manner of constructing and operating furnaces, whether cupola or reverberatory, used for smelting the ore of precious metals, in such a manner that the lining of the side or bottom may be renewed indefinitely from the outside of the furnace, as it melts in the inside. It furthermore consists in making such lining of a mixture of ore and flux, so that, as it wastes away, it is so much work accomplished.

T T' T are the basins, made of carbon blocks, or bricks made of compressed carbon. A is the cone, and B B' are the arches of the furnaces. C C' are the fireplaces. D D' D', &c., are boxes formed by partitions and shelves of cast iron, upon which the cone A is built. E E', &c., are plates fitting in the boxes D D' D'', &c., acting as pistons in the same, and pressed toward the centre of the furnace by the screws f' f' f'', &c., or any other proper appliances. M M' are similar boxes in the reverberatory furnaces, figs. 3 and 4, having their piston-plates N N' moved by the hydraulic presses P P'. F F' are flues, S S are blast-holes, and a a a are charging-holes. The stacks and proper condensing-apparatus are applied to the said furnaces, as may be desired.

Operation.

In the case of the furnace, figs. 1 and 2, or cupola-furnace, the boxes D D' D', &c., are filled with a concrete of the ore to be worked in the furnace, or any other ore which, by being melted or reduced, will add to the product of the furnace, and of a proper flux to cause the mass to adhere together and form a solid body. The fuel, and ore, with its due proportion of flux, and duly prepared for the operation, are fed, and the operation of smelting and reducing is carried on in the usual way; that is, new fuel and flux and ore are added occasionally, while metal and slag are drawn off from the bottom at stated times.

As the lining of the part most exposed to heat and action of the flux gradually melts away, the furnace gets larger in that part, but power being applied outwardly on the pistons E E', &c., the blocks of concrete in the boxes D D' D'', &c., will slide in the direction of the centre of the furnace, until, as they meet at their angles and form a perfect vault, they stop, and the furnace is again brought to its original size and shape.

When the pistons E have been pushed for a certain distance, they are moved back, and the space left between said piston E and the block of concrete is now filled and packed full with a new supply of concrete of ore and flux, (L, fig. 2,) and the pressure required to cause the blocks in the boxes D D', &c., to move is such that the concrete will always be perfectly compact and solid before it reaches that part of the furnace where it is applied to heat.

In the figs. 4 and 3 it is the hearth of the furnace which is to be renewed, and the boxes M M', pistons N N', worked by the hydraulic presses P P', represent and act in the same manner as the above-described arrangement in figs. 1 and 2. The ore is introduced by the holes a a a, and falls on the hearth of the furnace. The flame acts both on the pile of ore and on the hearth, and as that hearth melts away it is replaced by the outside or bottom; and, in all the cases which I have described, it is always the same thing I have in view, renewing the lining of the furnace from the outside, to make it a continuous working, and making the lining of a concrete of ore and flux, to save fuel, by producing a result out of what is always a loss in other furnaces in which the lining is made of bricks or clay.

Claims.

1. The combination of the boxes D D' D'' D''', &c., the pistons E E' E'', &c., and screws f' f' f'', &c., or their equivalents, with a cupola or blast-furnace, A, the whole arranged and operating in the manner set forth.

2. In blast and cupola-furnaces I claim making the lining of a composition of ore and flux, and renewing said lining from the outside by means and with the arrangement herein described.
3. The combination of the box M or M', the piston N or N', and press P or P', with a reverberatory furnace, arranged and operating in the manner specified.
4. Forming the hearth of a reverberatory furnace of a concrete of ore and flux, and renewing the same from the outside, without stopping the operation of the furnace, by means and with the use of the herein-described arrangement.

H. GENGEMBRE HUBERT.
